(57) **CLAIM**

The ornamental design for a handheld garment steamer, as shown and described.

DESCRIPTION

FIG. 1 is a left side perspective view of a handheld garment steamer showing my new design;

FIG. 2 is a left side elevation view thereof;

FIG. 3 is a rear side elevation view thereof;

FIG. 4 is a right side elevation view thereof;

FIG. 5 is a front elevation view thereof; and,

FIG. 6 is a top plan view thereof.

In the drawings, the broken lines in the figures depict portions of the design that form no part of the claim.

All portions not shown of the missing bottom plan view do not form any part of the claimed design.
